UNITED STATES PATENT OFFICE

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY

OIL STILL

Application filed January 19, 1925. Serial No. 3,216.

My present invention relates to oil stills and will be best understood from the following description and the annexed drawing of an illustrative embodiment of my invention, in which 10 is a bank of tubes connected to an upper drum 11 and a lower drum 12 and extending across a furnace chamber 13 at substantially 45° to the horizontal, the furnace chamber being provided 10 with a hot gas inlet 14 and a waste gas exit 15, the hot gases being provided from fuel burned on the chain grate 16.

A bridge wall 17 is provided between the hot gas inlet 14 and the waste gas exit 15 15 and extending to a point close to the tubes 10, this bridge wall, together with the relation of the several parts, defining a path for the heating gases entering through the inlet 14. From this inlet the gases pass upwardly 20 across the upper ends of the tubes 10 and then downward across the rear end of such tubes to the gas exit 15.

The still, in the illustrative form, is provided with one or more longitudinal drums 25 18, 19, the drum 19 being connected by tubes 20 with the lowermost of these drums 18, the latter being connected through the connections 21 and 22, respectively, with the upper drum 11 and the lower drum 12.

30 It will be understood that the specific form of the still may be widely varied and that the arrangement which I have described is chosen merely for the purpose of illustration. The same is true of the fuel-burning means, 35 it being obvious that any other form of fuel-burning means, such as an oil burner or a gas burner, may be used instead of the solid fuel-burning devices, which I have illustrated.

In oil stills, it has been found that if too 40 intense heat is applied to the tubes through which the oil to be heated is flowing, difficulties arise.

Heretofore it has been proposed to operate the fuel-burning means less efficiently in 45 order to keep down the temperature of the gases which first contact with the oil-circulating tubes. This has involved in some instances, the admission of excess air which, in reality, merely dilutes the combustion gases, 50 and consequently carries away an undue

amount of heat which such cold air abstracts from the burning gases.

In the arrangement illustrated in the drawing, I have overcome these difficulties by using some of the waste gases as a means 55 for diluting the incoming hot gases, so that, although the fuel is burned at its greatest efficiency and at its highest temperature, nevertheless the temperature is sufficiently reduced before the gases contact with the tubes 60 to prevent injury to the tubes, and, at the same time, the heat abstracted from the incoming hot gases is nevertheless utilized.

In the specific arrangement illustrated, I 65 accomplish this end by providing an opening or openings 23 in the bridge wall 17. The opening 23 provides a means by which some of the gases, after passing out of contact with the tubes 10, may be diverted from the exit 15 and returned to the front of the 70 bridge wall 17, there to mingle with the incoming gases from the inlet 14 and to be recirculated over the tubes 10.

It will be obvious that various means may be employed to so divert these waste gases, 75 but, in the form illustrated, I have shown an injector by which a jet of air or gases drawn from the waste gas flue will be blown through the opening 23 and thereby draw waste gases from the exit 15 and force them 80 into the hot incoming gases.

Gaseous fuel may also be blown through the opening 23, in which case the waste gases drawn through the opening 23 and returned to the furnace serve to reduce the flame temperature of combustion of the gaseous fuel on mingling with the air admitted to the furnace below what it would be without the return of the waste gases to the furnace.

The air or gas for operating the injector 90 is admitted to the pipe 24 extending across the bridge wall and one or more nozzles 25 directs a stream of this air or gas through the opening or openings 23 as described.

I claim:

1. In an oil still and its setting, a bank of inclined heating tubes extending from the front to the rear of said setting, a bridge wall extending across the setting intermediate the front and rear walls of said setting and 100

- extending upwardly to a point close to an intermediate portion of said tubes, said setting forming a furnace chamber including a hot gas inlet at the front of said bridge wall and a gas exit at the rear thereof, whereby the gases from said gas inlet flow upwardly in front of the said bridge wall across the front portion of the inclined tubes and then downwardly across the rear portion thereof to the gas exit, said bridge wall being provided with an opening furnishing communication between said gas exit and said gas inlet, and means for causing a portion of the waste gases to pass from said gas exit through said opening into said gas inlet.
2. In an oil still and its setting, a bank of inclined heating tubes extending from the front to the rear of said setting, a bridge wall extending across the setting intermediate the front and rear walls of said setting and extending upwardly to a point close to an intermediate portion of said tubes, said setting forming a furnace chamber including a hot gas inlet at the front of said bridge wall and a gas exit at the rear thereof, whereby the gases from said gas inlet flow upwardly in front of the said bridge wall across the front portion of the inclined tubes and then downwardly across the rear portion thereof to the gas exit, said bridge wall being provided with an opening furnishing communication between said gas exit and said gas inlet, and fuel means for causing a portion of the waste gases to pass from said gas exit through said opening into said gas inlet.

DAVID S. JACOBUS.
